SHEAR

William L. Ludwick, Mount Carmel, Conn., assignor to The Peck, Stow & Wilcox Company, Southington, Conn., a corporation of Connecticut

Application September 7, 1946, Serial No. 133,152

Term of patent 14 years

(Cl. D55—1)

To all whom it may concern:

Be it known that I, William L. Ludwick, a citizen of the United States, residing at Mount Carmel, in the county of New Haven and State of Connecticut, have invented a new, original, and ornamental Design for a Shear, of which the following is a specification, reference being had to the accompanying drawing, forming part thereof, in which:

Fig. 1 is a perspective view of a shear, showing my new design;

Fig. 2 is a front elevational view;

Fig. 3 is a side elevational view; and

Fig. 4 is a rear elevational view.

I claim:

The ornamental design for a shear, substantially as shown.

WILLIAM L. LUDWICK.
